UNITED STATES PATENT OFFICE.

FRANK R. SMITH, OF HOULTON, MAINE.

DESIGN FOR A GRATE.

SPECIFICATION forming part of Design No. 27,876, dated November 16, 1897.

Application filed September 27, 1897. Serial No. 653,265. Term of patent 14 years.

To all whom it may concern:

Be it known that I, FRANK R. SMITH, a citizen of the United States, residing at Houlton, in the county of Aroostook and State of Maine, have invented a new and original Design for Grates, of which the following is a specification.

The invention relates to a new and original design for grates.

10 The leading feature of the design resides in a corrugated grate provided with perforations, and a minor feature of the design consists in an alternate arrangement of the perforations in the raised or convex portions of 15 the grate and in the depressed portions or grooves.

In the drawings, Figure 1 is a perspective view of a grate showing my new design. Fig. 2 is a sectional view of the same.

20 Referring to the drawings, 1 designates a corrugated grate, forming on its upper face a series of convex portions or ribs 2 and concaved portions or grooves 3, located between

the ribs or convex portions, but the lower face of the grate has the ribs and grooves 25 reversely arranged, the rib of one face producing the groove of the other face.

The grate is provided with perforations 4, arranged at intervals in rows in the raised portions or ribs and in the depressed portions 30 or grooves. The perforations of the raised portions or ribs and the depressed portions or grooves are alternately arranged, the perforations of one series being located opposite the intervals of the perforations of the adjacent series.

What I claim is—

The design for a grate as herein shown and described.

In testimony that I claim the foregoing as 40 my own I have hereto affixed my signature in the presence of two witnesses.

FRANK R. SMITH.

Witnesses:

M. J. WEBBER,
